UNITED STATES PATENT OFFICE.

CHARLES ELLSWORTH ADAMSON, OF SHELTON, CONNECTICUT, ASSIGNEE TO ADDRESSOGRAPH COMPANY, OF CHICAGO, ILLINOIS, A CORPORATION OF ILLINOIS.

ADDRESSING ATTACHMENT FOR DUPLICATING-MACHINES.

1,209,410.

Specification of Letters Patent. Patented Dec. 19, 1916.

Application filed March 1, 1912. Serial No. 660,843.

To all whom it may concern:

Be it known that I, CHARLES ELLSWORTH ADAMSON, a citizen of the United States, and resident of Shelton, in the county of New Haven and State of Connecticut, have invented new and useful Improvements in Addressing Attachments for Duplicating-Machines, of which the following is a specification.

10 My invention relates to attachments for duplicating machines used to reproduce circular or imitation type-written letters or other matter in any desired quantity.

Imitation type-written letters are usually 15 printed by means of an inked ribbon passing over the type form, which letters are provided with the name and address of the party to whom they are to be sent by means of what is known as a "filling-in" operation 20 with a typewriter. The uneven impression resulting from this method, due to the different conditions under which the body of the letter and the name and address are printed and also due to the fact that the ribbon of the typewriter can seldom be matched 25 exactly with that of a duplicating machine is very objectionable.

The primary object of my invention is the provision of suitable mechanism by means of 30 which the above-mentioned objectionable features to a separate "filling-in" process are entirely eliminated.

Another object of my invention is the provision of an addressing device attachable to 35 present forms of machines, and more particularly to the form of machine disclosed in my Patent No. 1,015,256, dated January 16, 1912.

Another object is to provide an addressing 40 attachment in which the name plates, so called on account of their having the name and addresses of the parties included in a mailing list, for instance, are automatically discharged from the machine after the im- 45 print is taken therefrom.

A further object is to provide a means for receiving and successively arranging the name plates when delivered from the machine.

50 Still further objects are the provision of means for removing that portion of the ribbon passing over the name-plate so as to expose a portion of the auxiliary type-bearing member adapted to carry the name plate and 55 permit the placing of the name plate in

proper position relative to the body of the type form; to provide means for replacing the inking ribbon over the name plate so that the body of the letter with the matter carried by the name plate will be printed 60 during one printing operation; and to otherwise provide novel features of construction embodied in the mechanism for the purpose designed.

My invention consists in an addressing 65 mechanism, preferably in the form of an attachment, including a type form adapted to be printed simultaneously with the body of a letter.

It further consists in interchangeable devices carrying printing surfaces adapted to be used in conjunction with a body printing-form so that one portion of each letter or other sheet of paper may be printed with different matter than the corresponding portion of other letters or sheets.

It further consists in the combination of a type-bearing member, an impression member and a device permitting the use of different or auxiliary type forms for a portion of each sheet to be printed.

It further consists in the arrangement and co-operation of devices for the printing of different names and addresses or other special matter with each printing operation; and in the construction, arrangement and combination of parts to be hereinafter described and particularly pointed out in the subjoined claims.

In the drawings.—Figure 1 is a side elevation of a duplicating machine showing one embodiment of my invention applied thereto. Fig. 2 is a plan view of the same. Fig. 3 is a longitudinal section taken through a portion of the length of the machine in a plane indicated by line $x-x$, Fig. 2. Fig. 4, is an enlarged transverse section taken on line $y-y$, Fig. 1, looking in the direction of the arrow crossing said line. Fig. 5 is a detached perspective view of the addressing attachment removed from the duplicating machine. Fig. 6 is a side elevation of the device and the adjacent end of the duplicating machine to which it is applied, showing the parts of the addressing device in a different position from that shown in Fig. 1. Fig. 7 is a longitudinal section on a reduced scale taken on line $x-x$, Fig. 2, showing the parts in corresponding positions to those shown in Fig. 6.

Referring now to the drawings in detail, similar numerals of reference refer to similar parts throughout the various figures.

The reference numeral 10 designates a duplicating machine mounted on a support 11. It comprises a frame 12 having a flat bed or type-bearing member 13 provided with upstanding guide flanges 14 to which is held for reciprocating movement a carriage 15 having an impression roller 16 arranged so that in moving the carriage forward or in the direction of the arrow 17, Fig. 1, the impression roller is positioned for printing action; while, when returning the carriage, said roller is in inoperative or idle position, and as these members form no part of my invention, detailed description of the same is thought to be unnecessary.

The type-bearing member 13 has placed thereon a type-chase 18 which in the present embodiment of the invention has a portion cut away, as at 19, for a purpose to appear hereinafter and within said type-chase are arranged the type 20 to form the desired reading matter for the body of a letter or the like, said type-chase and type may be referred to as the main "type-form," which may include anything capable of making an impression.

Between the type-chase 18 and flanges 14, yielding bearing tracks 21 are placed which are of sufficient length to extend beyond the forward edge of the duplicating machine, and co-acting with said tracks 21 are the rollers usually employed which are rotatable with the impression roller 16.

Referring now to the addressing attachment, which term I intend to be generic and include any mechanism by means of which a different printing device may be used with each impression made from the "type-form" on the type-bearing member, 23 designates an auxiliary type-bearing member adapted during printing operation to occupy the space 19 formed by cutting away a portion of the chase 18. Said auxiliary type-bearing member is to be actuated by suitable mechanism for the purpose of removing the auxiliary type-forms 24 therefrom; said auxiliary type-forms, in the embodiment of my invention shown, are type-holders used as name plates and have a plurality of rows of type 25 forming the name and address of the party to whom the letter is to be sent. This name plate may be of any approved construction and is adapted to be placed onto the auxiliary type-bearing member 23 by the operator and be automatically removed therefrom directly after the printing operation. Said auxiliary type-bearing member comprises a substantially flat plate 26 having a pair of legs 27 at its rear end to hold the upper surface of the plate 26 in such position relative to the printing face of the main type-form that when the type-holder

or auxiliary type-form 23 is placed upon the auxiliary type-bearing member, the face of the type on the latter will be in absolute alignment with the face of the main type-form.

To the rear end of the plate 26 is secured a transverse rod 28 fastened to one end of a rock-arm 29 which is in turn secured to a rock-shaft 30 journaled for rocking movement in a frame 31 adapted to be secured to the support 11. The rock-arm 29 has its upper end bifurcated, as at 32, to receive the rod 28 and when the rock-shaft 30 is rocked in its bearings the rock-arm is swung from its normal position, shown in Fig. 3, to the position shown in Fig. 7, thus discharging the name plate from the auxiliary type-bearing member, which latter is carried forward and inclined downward by said rock-arm. To one end of said rock-shaft an actuating lever 33 is secured which has a right-angled extension 34 at its lower end to which extension is secured one end of a retractile spring 35 whose other end is attached to a handle 36 pivotally secured to the support 11, as at 37, and adapted to be held in the operative position shown in Figs. 1, 5 and 6, or in an inoperative position, as shown in dotted lines in Fig. 6. When the handle 36 is in operative position a stop 36^a engages the end of the support 11 and the retractile spring 35 is placed under tension so as to draw the right angle extension 34 downward and the main portion 33 of the actuating lever rearward. The stop 36^a on said handle prevents rearward movement of the latter while the spring 35 prevents forward movement of the same, except when manually swung into inoperative position against the action of said spring.

Upon moving the carriage 15 forward an outstanding pin 38 thereon comes in contact with the actuating lever 33 and serves to swing the same against the resisting action of the spring 35, and owing to said lever being secured to the rock-shaft 30 the latter is caused to rock and swing the rock-arm 29 through an arc of a circle, carrying with it the auxiliary type-bearing member so as to position the same that the auxiliary type-form thereon will be free to gravitate therefrom.

When the handle 36 is swung into the operative position shown in Figs. 1, 5 and 6, the retractile spring 35 is disposed beneath the axis of the rock-shaft 30 to which the actuating lever is secured; or in other words, acts upon the extension 34 of said lever at one side of the dead center. This causes the upper end of the actuating lever to be retained within the path of pin 38 so that it will be engaged by said pin during the forward movement of the carriage and be swung forward the required distance without bringing the extension 34 of said lever

to its dead center; consequently when the carriage is moved rearward the spring 35 acts to swing the lever rearward so as to position said lever to be again engaged upon 5 the forward movement of said carriage. In this manner the lever 33 is always properly positioned to be struck by the pin 38; at the same time the handle 36 is retained in the position shown in Fig. 1 by the spring 35.

10 When swinging the handle 36 upwardly, the point of connection thereto of spring 35 is brought above the pivot 37 of said handle and this action changes the line of draft of said spring so that it is disposed above the 15 axis of the rock-shaft 30; consequently drawing the extension 34 of the actuating lever upwardly and forwardly and retaining the upper end of said lever in its foremost position out of reach of the pin 38 on the carriage. When the handle 36 is in its inoperative position, the stop 36^a thereon engages the end of support 11, but at a higher point than when said handle is in operative position. It is apparent, therefore, that the 20 spring 35 is under tension at all times and that the handle 36 serves to change the line of draft of said spring so that the latter acts to draw the actuating lever into its foremost or inoperative position when the said handle 25 is swung upward and into its rearward or operative position when said handle is swung downward.

30 The frame 31 comprises two side members 39 connected at an intermediate point by a cross-member 40 having a pair of rearwardly extending flanges 41 at its upper edge and connecting the rear ends of said side members is a supporting bar 42 on which is adapted to rest a name plate rack 43 comprising side bars 44, side confining walls 45 and a slidable head 46. The side bars extend rearwardly and fit underneath the flanges 41 on the cross-member 40 of the frame so as to removably hold the rack 45 on said frame.

The auxiliary type-forms, or more specifically the name plates, are delivered from the auxiliary type-bearing member 23 into the rack 43 and for the purpose of assuring proper introduction into the rack the sides 45 of the latter have upward extensions 47 at their inner ends which are slightly flared outwardly at their upper ends to facilitate the introduction of the name plates 55 into the rack.

A second rock-shaft 48 is journaled in the side members 39 between the cross member 40 and the supporting bar 42, and held loosely on said rock-shaft is a pusher-head 60 49 having one end of a rod 50 pivotally secured thereto, which rod extends rearwardly and has pivotal connection with a downward extension 51 of the rock-bar 29 so that when said rock-bar swings forward to 65 carry the auxiliary type-bearing member

into an inclined position for discharging the name plate, the downward extension 51, thereof swings rearwardly and through the intervention of the rod 50 swings the pusher-head 49 from the position shown in Fig. 3 70 to that shown in Fig. 7, thus providing sufficient room in front of the pusher-head to receive the name plate from the auxiliary type-bearing member. When the parts are returned to normal position, said name plate 75 is pushed forward by said pusher-head so as to properly place the name plate within the rack. A slidable head 46 is held to the sides of the rack by frictional contact and is moved forwardly step by step as the pusher-head 80 49 pushes the successive name plates forward. The name plates thus delivered are therefore held between said slidable-head and said pusher-head so that they at times retain a substantially vertical position. In this manner the successive name plates are delivered into the rack in proper 85 succession and crowded forward until the rack is filled when they may be removed from the rack or the rack removed with the 90 name plates therein after which an empty rack may be placed in position to receive the name plates from the auxiliary type-bearing member.

Secured to the outer ends of the rock-shaft 48 are two upwardly directed arms 52 one of which has a rearward extension 53, to the extremity of which is secured one end of a retractile spring 54 having its other end secured to the adjacent side member 39 100 of the frame 31. With a view of limiting the upward swinging movement of said extension 53 and consequently the rocking movement of the shaft 48, a stop 55 on said side member is engaged by a web 56 formed on 105 the rear side of said rearward entension 53. At the upper ends of said arms 52 laterally-disposed sleeves 57 are provided to which are held rearwardly-directed arms 58 by means of screws 59 threaded into said 110 sleeves and surrounded by expansion springs 60, one of which bears with one end against the inner face of its co-acting arm 58 and with its other end against the outer end of the sleeve 57 while the other bears with one 115 end against the head of the screw 59 and with its other end against the inner face of its co-acting arm 58. By tightening or loosening the screws 59, the tension of the 120 springs can be regulated so as to govern the resistance placed against the swinging action of the arms 58.

The rock-shaft 48, and arms 52 and 58 constitute a swinging ribbon frame, and secured to the inner side of the arms 58 at 125 their rear or free ends are spool receiving rollers 61 which are faced with rubber or other suitable material to provide the necessary friction for rotating said rollers when traveling in contact with the upper faces 130

of the yielding tracks 21. These arms 58 are held in position by gravity and in the rolls thereof, which are hollow, the opposite ends of a ribbon spool 63 are secured in 5 such a manner that said spool rotates with said rollers. Attached to the spool and rolled thereonto is an inking ribbon 64, which, when the parts are in normal position shown in Fig. 3, passes over the auxiliary type-form, and the main type form 10 and has its opposite end secured to a ribbon spool mounted to be rotated by suitable take-up mechanism 65, which take-up mechanism is actuated by the reciprocating movements 15 of the carriage, as clearly shown in my Patent No. 1,015,256, dated January 16, 1912. The inking ribbon is therefore adapted to be unwound from the spool of the swinging ribbon frame during the successive printing 20 operations and wound onto the ribbon spool at the opposite end in a manner common to machines of this type.

Pivoted secured to the actuating lever 33, near its upper end is a hook-lever 66. Said hook-lever extends both forwardly and rearwardly from its pivotal point of connection to said actuating-lever and near its forward end has a hook 67. Said hook-lever extends forwardly a distance beyond 25 said hook and enters a loop 68 on the outer side of one of the levers 52, the extremity of said lever 66 being bent laterally, as at 69, to prevent disengagement of said hook-lever from said last-mentioned lever 52.

30 The operation of the device is as follows:—Normally the parts are in the position shown in Fig. 1, in which position the friction-rollers 61 rest upon the guide tracks 21 at their forward ends; the ribbon passes 35 over the main type-form and auxiliary form so that the parts are in position for printing action, in which position the hook 67 of the hook-lever 66 is disengaged from the swinging ribbon frame comprising the bars 40 52 and 58.

45 Preparatory to printing, a sheet of paper is laid upon the ribbon covered type-forms and the printing operation occurs during the forward movement of the carriage, immediately the impression-roller 16 in said carriage has passed over both type-forms the upper end of the actuating-lever 33 is engaged by the outstanding pin 38 or some other portion of the carriage, carrying said 50 lever forward with the carriage. This forwardly swinging action of the actuating-lever causes the shaft 30 to rock, thus drawing the auxiliary type-bearing member forward and downward into an inclined position and at the same time drawing the 55 pusher-head 49 rearward to provide a space in front of the same to permit the auxiliary type-form to be delivered from said auxiliary type-bearing member into the name 60 plate rack 43. During this forward move- 65

ment of the actuating-lever 33, the hook-lever 66 is forced forwardly so as to bring the hook 67 thereof in engagement with the loop 68 on the adjacent lever 52. Now upon drawing the carriage backward the spring 70 75 acts to return the actuating-lever 33 to normal position, during which action the auxiliary type-bearing member is moved upwardly and rearwardly onto the main type-bearing member and the pusher-head is moved forwardly to position the last delivered name plate properly within the rack. At the same time the hook-lever 66 which remains engaged with the loop 68 draws the swinging frame rearwardly and with it the ribbon spool 63. During this rearward movement of the swinging frame, the friction rollers 61 thereof travel in contact with the tracks 21 and are rotated and by reason of the ends of the ribbon spool 63 being held 75 within said friction rollers, said ribbon spool is rotated also and winds up the ribbon so as to expose the auxiliary type-bearing member. The operator places a new name plate or auxiliary type-form upon the auxiliary type-bearing member and when this is done, he depresses the rearwardly extending portion of the hook-lever 66, whereupon the spring 54 comes into action to swing the ribbon carrying frame rearwardly, thus causing the friction rollers 61 thereof to travel rearwardly in contact with the guide tracks 21 and uncoil the ribbon to the extent it was wound up by and during the rearward travel of said friction rollers, thus covering the auxiliary type-form with the inking-ribbon and placing said ribbon in position to permit proper placement thereon of a sheet of paper to be printed. The machine is then in condition for the next forward movement 100 of the carriage to print the next sheet of paper.

When it is desired to print a common form without a change of name and address or change of other matter, the hand-lever 36 105 may be swung into the position shown in dotted lines in Fig. 6, in which position the tension on the spring 35 is removed and the various parts are held in a position in which they will not be actuated by the reciprocating movement of the carriage.

110 While I have shown my invention as an attachment, it is apparent that it may be embodied in a duplicating-machine, and although the invention is designed primarily 115 as a "filling-in" device permitting change of matter on each sheet printed, it is to be understood that it may be used for addressing envelopes, post-cards, and the like, in which case the main type-form would be dispensed 120 with.

125 I have herein shown and described what I now consider the preferred embodiment of my invention, but many changes in form, arrangement and construction may be re-

sorted to without departing from the spirit of my invention or sacrificing any of its advantages.

Having thus described my invention, what I claim is,—

1. The combination with a printing machine having a flat type-bearing member and a reciprocating impression member, of an auxiliary type-bearing member normally positioned on said flat type-bearing member, mechanism for moving said auxiliary type-bearing member out of normal position and adapted to be actuated by said reciprocating impression-member, and means for positioning said mechanism to hold said type-bearing member out of normal position and to prevent actuation of said mechanism by said impression-member. 70
2. An addressing attachment for a machine of the character described, comprising a frame, a rock-shaft journaled in said frame, a spring-positioned lever secured to said rock-shaft and adapted to be actuated in one direction by a part of said machine, a second lever secured to said rock-shaft, and an auxiliary type-bearing member connected with said last-mentioned lever so as to be moved into and out of printing position. 75
3. An addressing attachment comprising a frame, a rock-shaft mounted in said frame, a lever secured to said rock-shaft and having a right-angle extension, a retractile spring secured with one end to said extension, a swinging arm to which the other end of said spring is secured, a second lever on said rock-shaft, and a type-bearing member connected to said last mentioned lever so as to be moved into and out of printing position. 80
4. In combination with a type-form receiving-rack, an addressing attachment comprising a frame, a rock-shaft mounted in said frame, a lever secured to said rock-shaft and extending in two directions therefrom, a type-bearing member secured to one end of said lever, a pusher-head in said receiving-rack pivotally mounted to swing therein, and a link connecting said pusher-head with the opposite end of said lever. 85
5. In a machine of the character described, the combination with a main type-form and an impression member coöperating therewith, of changeable auxiliary type-forms adapted to be successively used w. h. said main type-form, a swinging frame, a ribbon spool rotatable in said swinging frame, an inking ribbon wound around said spool and normally passing over said type-forms, and means for causing said swinging frame to carry said ribbon spool beyond the auxiliary type-form in use. 90
6. In a machine of the character described, the combination with a frame having a type-bearing member and an impression member 95
- coöperating therewith, of a ribbon support having alined friction rollers adapted to travel in contact with friction surfaces on said machine, and be rotated thereby, a ribbon spool rotatably held to said rollers, and means to cause said support to move so as to carry said spool to a different position and the ribbon to be wound thereon, for the purpose set forth. 100
7. In a machine of the character described, the combination with a frame having a type-bearing member and an impression member, of a swinging frame secured to said first-mentioned frame and having a pair of alined friction rollers adapted to travel in contact with a plane surface on said first-mentioned frame, a ribbon spool rotatably held to said friction rollers, and a ribbon wound around said spool and passing therefrom, said frame upon being swung causing said ribbon spool to be moved to a different position and be rotated by the medium of said friction rollers to expose a portion of the machine beneath the ribbon. 105
8. In a machine of the character described, the combination with a type-bearing member having a main type-form thereon, a series of auxiliary type-forms adapted to be used successively in conjunction with said main type-form, means for delivering the auxiliary type-forms successively after successive printing operations, an inking ribbon passing over the main type-form and the auxiliary type-form in use, an impression member coöperating with said two last-mentioned type-forms, and means for winding up a portion of said ribbon after each printing operation for bringing the same beyond said printing position for said auxiliary type form and allow another auxiliary type form to be placed in position for printing. 110
9. In a machine of the character described, the combination with a frame having a type-bearing member, of a ribbon-frame secured to said first-mentioned frame and comprising a pair of levers mounted for swinging movement, a pair of arms pivotally secured to said levers at their free ends, a pair of friction rollers at the free ends of said arms adapted to travel in contact with friction surfaces on said first-mentioned frame, a ribbon-spool having its ends held in said friction rollers and adapted to rotate therewith, and a ribbon wound around said ribbon-spool and adapted to be wound thereon upon swinging of said levers. 115
10. In a machine of the character described, the combination with a frame having a pair of tracks and a type form situated between said tracks, of a frame used in conjunction therewith, a rock-shaft mounted on said frame, a pair of levers secured to said rock-shaft, one of said levers having a lateral extension, a retractile spring having 120
- 125
- 130

- one end secured to said extension and its other end secured to said first-mentioned frame, a pair of arms pivotally held to the free ends of said levers, a pair of friction rollers at the free ends of said arms traveling in contact with said tracks, a ribbon spool held to said friction rollers and rotatable therewith, an inking ribbon wound around said spool, and means to swing said levers in one direction against the tension of said spring to cause rotation of said ribbon spool and to cause the ribbon to be wound thereon.
11. In a machine of the character described, the combination with a type bearing member having a pair of tracks, of a spool supporting frame movable back and forth and having friction rollers traveling in contact with said tracks, a ribbon spool having its ends secured in said friction rollers, and a ribbon wound around said spool, for the purpose set forth.
12. In a machine of the character described, the combination with a frame having a type-bearing member provided with a pair of tracks, of a spool-supporting frame supported by said first-mentioned frame and comprising two swinging levers, screws threaded into the free ends of said levers, a pair of arms arranged on said screws for swinging movement, springs surrounding said screws and exerting pressure against said arms, friction rollers rotatably mounted on said arms and arranged for rolling contact with said tracks, a ribbon spool rotatably held to said friction rollers, an inking ribbon wound around said ribbon spool, means for moving said spool-supporting frame in one direction, and a spring for moving said spool-supporting frame in an opposite direction.
13. The combination with a main type-bearing member having a type-form thereon, an auxiliary type-bearing member adapted to receive auxiliary type-forms in succession, an impression member coöperating with said type-bearing members, an inking ribbon arranged to travel over said type-bearing members, and a ribbon take-up mechanism at one end of said main type-bearing member, of an actuating lever adapted to be actuated by said impression member, connection between said actuating lever and said auxiliary type-bearing member to cause the latter to deliver the type-forms therefrom, a ribbon supporting frame mounted for movement in two directions and having one end of said inking ribbon secured thereto, means of connection between said frame and said actuating lever to cause said frame to move in one direction and expose said auxiliary type-bearing member, and a spring to move said frame in its opposite direction.
- In testimony whereof, I have affixed my signature in the presence of two subscribing witnesses.
